JUSTIFYING SPACEBAND

Adelbert L. Child, Ozone Park, N. Y., assignor to
 Mergenthaler Linotype Company, a corpora-
 tion of New York

Application February 21, 1936, Serial No. 65,018

14 Claims. (Cl. 199—68)

This invention relates to justifying spacers or spacebands, such as are used in the typographical composing and casting machines known commercially under the trade mark "Linotype", and kindred machines, for the justifying of composed lines of matrices prior to the casting operations.

These spacers or spacebands are ordinarily formed of two main parts, viz., two oppositely wedge-shaped members, one shorter than the other and known as the stationary part and provided with ears by which it is held against movement during justification, and the second or longer member which is slidably connected (by tongue and groove portions) to the shorter one in such manner as to enable it to be forced upwards through the composed line for effecting the justification.

Heretofore, the tongue and groove portions of the spacebands have had at least one pair of their contacting surfaces in the same plane as the surfaces of the two members that are in sliding contact. This construction has made difficult, if not impossible, to machine the contacting surfaces by grinding and has necessitated careful milling and fitting of the parts.

According to the present improvements, the tongue and groove portions that guide the two members one on another and hold them against lateral separation are offset or displaced in their entirety out of the plane of the contacting surfaces of the members, with the result that these surfaces may be ground with facility even though the tongue and groove portions are not.

Referring to the drawing which shows the parts of the spaceband on a greatly enlarged scale,

Fig. 1 is a face view, showing the shorter member in its uppermost position in solid lines and in its lowermost position in dotted lines;

Fig. 2 is a longitudinal section taken on line 2—2 of Fig. 1;

Fig. 3 is a face view of the shorter member, showing the face opposite to that illustrated in Fig. 1;

Fig. 4 is an edge view of the member shown in Fig. 3;

Fig. 5 is a horizontal section taken on line 5—5 of Fig. 3;

Fig. 6 is a horizontal section taken on line 6—6 of Fig. 1;

Fig. 7 is a horizontal section taken on line 7—7 of Fig. 1; and

Fig. 8 is a horizontal section similar to Fig. 7, but illustrating a standard form of spaceband devoid of the present improvements.

A spaceband of the kind referred to comprises

two wedge-shaped members A and B secured together for relative slidable movement, the shorter member A being provided with ears A¹ by which it is held against vertical movement during justification. The member A is machined to a good finish along its marginal edges a to provide a plane surface for sliding contact with the member B; and in its lower portion, intermediate the marginal surfaces, it is formed with a raised wedge-shaped portion A² that cooperates in a manner hereinafter described with the longer member B to hold the parts against separation.

The longer wedge member B has formed in it, a longitudinal slot or recess B¹ terminating just short of the upper end of the member, and extending entirely through the member except in the lower portion or thick end of the wedge. Here too, the member B, to provide a plane surface for contact with the member A, is machined to a good finish along its marginal portions b contiguous to the slot B¹. The slot B¹ is adapted to receive the wedge-shaped portion A² of the shorter member and cooperate with it to guide the members in their relative sliding movement during justification.

The members A and B are held against separation laterally by a tongue and groove connection, the opposed edges of the slot or recess B¹ presenting bevelled tongues B² and the lateral edges of the wedge portion A² presenting complementary bevelled grooves A³. During assembly of the parts, the wedge portion A² is slid into the recess B¹ from the open or lower end thereof, and the wedge member B is thereafter provided with a pin B³ adjacent its lower end which acts as a stop for the wedge member A and thus prevents the parts from sliding apart longitudinally when in use.

In order more clearly to appreciate the differences between the improved spaceband and the standard form heretofore in use, reference may be had to Fig. 8 which depicts a horizontal section through the standard form of spaceband and wherein, for purposes of distinction, the longer wedge-shaped member is designated C, the shorter member D, the raised portion on the shorter member D¹, the grooves formed therein d, and the complementary tongues of the longer member c. It will be noted that one face, both of the tongue portions c and the groove portions d, are in the same plane as, and indeed are extended portions of, the surfaces of the members C and D that are in sliding contact. This arrangement has necessitated very accurate machining of all the contacting surfaces as well as careful fitting

of the cooperating parts, and even then standardization has been almost impossible. Furthermore, it has practically precluded the grinding of the surfaces (which is most desirable for the proper working of the spaceband during justification) because obviously the grinding tool or wheel can not extend beneath the overhanging portion that presents the upper surface of the groove a .

In the new or improved construction, the grooves A^3 in the wedge portion A^2 are in their entirety offset from or raised above the plane of the contacting surfaces of the two members A and B, i. e., the wedge portion A^2 presents a pair of shoulders A^4 at its opposite edges and extending throughout its entire length. The width of the wedge portion A^2 is widest in the region of the shoulders and as the outer faces thereof constitute one of the faces of the groove A^3 , it is apparent that no portion of the grooves extends beyond the lateral limits of the shoulders. With this arrangement, the grooves A^3 and the marginal surfaces a of the member A are entirely independent, and the latter may therefore be ground without having to grind the grooves.

25 In order to accommodate the shoulder portions A^4 , the tongues B^2 of the member B are cut out or recessed as at B^4 , along the marginal surfaces b . Here too, it will be seen that the marginal surfaces b are independent of the recessed portions B^4 and can be machined by grinding without having to grind said recessed portions.

Of course, the grooves A^3 and the tongues B^2 will have to be machined, as usual, but as these parts no longer form any portion of the sliding bearing surfaces of the finished spaceband, the machining need not be so accurately done, since their function now is only to guide one member along the other and to hold the parts against separation laterally. Indeed the fit between the 40 cooperating tongue and groove portions may be what can be characterized as a "careless" one.

The improved spaceband presents many advantages over the old. For example, by setting up proper tolerances, the members A and B can 45 be standardized, thus rendering corresponding parts interchangeable and thereby materially reducing cost, both as regards original manufacture and repair of the parts. Moreover, the behavior of the new spaceband in use is far superior to that of the old due to the machine grinding of the bearing surfaces which slide upon each other smoothly and easily as the spaceband is expanded during justification.

In the accompanying drawing, the invention 55 has been shown merely by way of example and in preferred form, and obviously many variations and modifications may be made therein which will still be comprised within its spirit. It is to be understood, therefore, that the invention 60 is not limited to any specific form or embodiment, except insofar as such limitations are specified in the appended claims.

Having thus described my invention, what I claim is:

65 1. A justifying spaceband including, in combination, a pair of relatively movable complementary wedge-shaped members presenting inner surfaces in bearing contact, and means for guiding the members in their relative movement, said means in their entirety being offset from the plane of the bearing surfaces.

70 2. A justifying spaceband including, in combination, a pair of relatively movable complementary wedge-shaped members presenting inner surfaces in bearing contact, and means for

guiding the members in their relative movement, said means including a tongue formed on one of said members, and a complementary groove formed in the other member to receive the tongue, said tongue and groove portions in their entirety being offset from the plane of the bearing surfaces.

75 3. A justifying spaceband including, in combination, a pair of relatively movable complementary wedge-shaped members presenting inner surfaces in bearing contact, one member being formed with a raised wedge-shaped portion formed in its lateral edges and spaced from the plane of the bearing surfaces with a groove arranged to receive a complementary tongue formed in the other member for guiding said members in their relative movement.

80 4. A justifying spaceband according to claim 3, wherein the tongue therein mentioned is likewise spaced from the plane of the bearing surfaces.

85 5. A justifying spaceband including, in combination, a pair of relatively movable complementary wedge-shaped members presenting inner surfaces in bearing contact, one member being formed with a raised wedge-shaped portion presenting, at its opposite edges, shoulders offset from the plane of the bearing surfaces and grooves adjacent said shoulders, and the other member presenting tongues interfitting said grooves as well as recesses to accommodate said shoulders.

90 6. A justifying spaceband including, in combination, a pair of relatively movable complementary wedge-shaped members, one shorter than the other, and the two presenting inner surfaces in bearing contact, said shorter member having a raised wedge-shaped portion formed in its opposite edges with means adapted to interfit complementary means formed on the longer member to guide said members in their relative movement, while holding them against relative facewise displacement, the bearing surface on the shorter member terminating at the lateral edges of said raised wedge-shaped portion.

95 7. A justifying spaceband including, in combination, a pair of relatively movable complementary wedge-shaped members, one shorter than the other, and the two presenting inner surfaces in bearing contact, said shorter member having a raised wedge-shaped portion formed in its opposite edges with grooves adapted to interfit complementary tongue portions formed on the longer member, the bearing surface of the shorter member terminating at the outer lateral extremities of the grooves.

100 8. A justifying spaceband including, in combination, a pair of relatively movable complementary wedge-shaped members, one shorter than the other, and the two presenting inner surfaces in bearing contact, said shorter member having a raised wedge-shaped portion formed in its opposite edges with grooves adapted to interfit complementary tongue portions on the longer member, the bearing surface on the shorter member terminating at the outer lateral extremities of the grooves formed in the wedge-shaped portion, and the bearing surface of the longer member terminating at the base of the tongue portion.

105 9. A justifying spaceband including, in combination, a pair of relatively movable complementary wedge-shaped members, one shorter than the other, and the two presenting inner surfaces in bearing contact, said shorter mem-

ber having a raised wedge-shaped portion presenting at its opposite edges shoulders offset from the plane of the bearing surfaces and grooves adjacent said shoulders, and said longer member presenting complementary tongues interfitting said grooves and recesses to accommodate the shoulders, the bearing surface on the shorter member terminating at the lateral edges of the shoulder portion, and the bearing surface of the longer member terminating at the lateral edges of the recesses which accommodate the shoulder portions.

10. A justifying spaceband including, in combination, a pair of relatively movable complementary wedge-shaped members, one shorter than the other, and the two presenting inner surfaces in bearing contact, and means for guiding the members in their relative movement, said means including a raised portion on one of said members, and a recessed portion in the other of said members, said raised portion and said recessed portion being formed in their lateral edges with complementary interfitting elements located in their entirety in offset relation to the plane of the bearing surfaces.

11. A justifying spaceband including, in combination, a pair of relatively movable complementary wedge-shaped members, one shorter than the other, and the two presenting inner surfaces in bearing contact, the shorter member having a raised portion presenting at its opposite edges a pair of shoulders spaced from the lateral edges of said member to provide marginal portions thereon, and the longer member having a depressed portion presenting shoulder recesses likewise spaced from the lateral edges of said member to provide marginal portions thereon, and com-

plementary interfitting elements formed in said raised and depressed portions and arranged adjacent the shoulders and the recesses, respectively.

12. A justifying spaceband including, in combination, a pair of relatively movable complementary wedge-shaped members presenting inner surfaces in bearing contact, said surfaces being machine-ground to provide a smooth and easy sliding motion between the two members, and interfitting complementary means formed on the two members for guiding them in their relative sliding movement while holding them against relative facewise displacement.

13. A justifying spaceband including, in combination, a pair of relatively movable complementary wedge-shaped members, one shorter than the other, and the two presenting inner surfaces in bearing contact, said shorter member having a raised wedge-shaped portion formed in its opposite edges with grooves adapted to interfit complementary tongue portions formed on the longer member, the bearing surface of the shorter member being located beyond the outer lateral extremities of the grooves.

14. A justifying spaceband including, in combination, a pair of relatively movable complementary wedge-shaped members, one shorter than the other, and the two presenting inner surfaces in bearing contact, said shorter member having a raised wedge-shaped portion formed in its opposite edges with grooves adapted to interfit complementary tongue portions formed on the longer member, the bearing surface of the shorter member terminating short of the inner edges of the complementary tongue portions on the longer member.
